United States Patent Office.

BENJAMIN D. SANDERS, OF WELLSBURG, WEST VIRGINIA.

Letters Patent No. 101,315, dated March 29, 1870.

IMPROVEMENT IN MACHINE FOR COMPRESSING WOOD TENONS.

The Schedule referred to in these Letters Patent and making part of the same.

To all whom it may concern:

Be it known that I, BENJAMIN D. SANDERS, of Wellsburg, in the county of Brooke and State of West Virginia, have invented a new and useful Improvement in Compressing Wooden Tenons and Rounds; and I do hereby declare the following to be a full, clear, and exact description thereof, reference being had to the accompanying drawing making a part of this specification, in which—

Figure 1 is a side view of one form of my machine, illustrative of my mode of operation;

Figure 2 is a front elevation of the same;

Figure 3 is a side view of a cylinder of wood, with a "round" compressed on each end; and

Figure 4 is a sectional view of such a round inserted in a hole of corresponding size, and tightened therein by the swelling of the forward or outer end of the "round."

Like letters of reference indicate like parts in each.

Heretofore, in the manufacture of chair-rounds, hoe and rake-handles, carriage-spokes, &c., the tenon part has been usually made by the process of turning, or sometimes by shaving, and the tenon was then fastened in its place by glueing or wedging, when any such particular fastening was required.

My invention includes not only a machine for making such tenons, but also the mode of making and fastening them, and is applicable to the manufacture of chair or other furniture "rounds," including rounds on the backs and arms, to making tenons on wooden rake-handles, rake-teeth, hoe-handles, hatchets, rounds on broom-handles, carriage-spokes, &c., and generally to the manufacture of all kinds of tenons which are round when finished, or which from a compressed round can be cut to the shape desired; and

The nature of it consists in the construction of improved devices for compressing cylindrical wooden forms.

To enable others skilled in the art to make and use my invention, I will proceed to describe its construction and manner of operation and use.

Any suitable frame-work, *a*, supports a cylindrical roller, *b*, which is operated by power communicated in any known way through an axle, *b'*.

Attached to any suitable part of the frame *a* is a segmental concave, *c*, made with a curvature of a radius a little longer than the radius of the wheel *b*, and adjustable on the frame *a* by set-screws *d*, which are tightened and loosened in the slots *d'*, and by a radially-acting set-screw, *d''*, though other equivalent means of adjustment may be substituted therefor.

This segmental concave *c* is adjusted outside the wheel *b* in the same plane, and so that the distance between the two at the feeding-end, as at *e*, shall be at least equal to the diameter of the wooden cylinder to be introduced therein, and so that the distance be-

tween the two at the opposite end *e'* shall be equal to the diameter of the tenon to be formed.

In order to secure a tenon of only the desired length, I insert between the roller *b* and concave *c* a gauge-plate, *i*, which is held in place by bolts passing back through the frame *a*, and there is adjusted by screws *o* thereon.

By setting this plate forward or backward, I regulate the length of "round" to be rolled or compressed.

The article *m* on which the "round" *m'* is to be formed is then introduced at the end *e* in such position that its axis shall be parallel with the axle *b'* of the wheel *b*, and by the revolution of the wheel *b* it is rotated through between the wheel *b* and its concave *c*, and the part caught therein is compressed and reduced to the form shown at *m'*.

In some kinds of work a groove, *n*, is required at the inner or base end of the round *m'*. To make this I construct the wheel *b* and concave *c*, one or both, with a bead, *n'*, on the outer edge.

The surfaces by which the rolling is done and the fiber of the wood compressed, instead of being curved as shown, may be made straight, arranged with reference to each other as described, and a reciprocating motion communicated to one, by which the same results will be secured.

In broom-handles and some other articles a compressed round is desired at a little distance from the end of the handle, onto which compressed part the broom-part is to be bound or otherwise fastened.

To make a compressed "round," such as is there required, I set the gauge *i* back from the roll *b* and concave *c* the required distance, so that the broom-handle may project past the working-faces of the roller and concave, the frame *a* being so shaped as to admit of such adjustment, and then roll and compress the round in the manner already described.

In some articles of manufacture, as hatchet-handles, an oval tenon is required, or a tenon of other than cylindrical form. To make such I compress a "round" in the manner above set forth, of a diameter at least equal to the maximum length of the cross-section of the tenon desired, and then turn down or otherwise reduce such compressed round to the oval, square, or other form required.

One of the chief advantages of this mode of making tenons or rounds is that, when they are inserted in or covered by the parts they are designed to fill, a little moisture applied directly to them, or in some cases the moisture of the atmosphere, will cause the fibers of the wood so compressed to swell or expand, or to resume their previous relation to each other.

This feature is illustrated in fig. 4, where *s* represents a compressed tenon, inserted in a hole or mortise in the block *s'*, with its end *s''* projecting through.

A little moisture applied in the shape of glue or

otherwise to the tenon *s*, just before inserting or afterward, will cause the compressed fibers of the wood to expand as shown, and make a dovetail-joint so secure that it can be broken only by splitting the block *s*.

In turning or otherwise preparing the rounds before rolling them as described, the groove *n* may be cut by the turning-chisel or other suitable tool, and the round may then be fed into the machine described, so that the bead *n'* shall come exactly in the groove, in which case the gauge may be dispensed with, the bead *n'* answering the same purpose.

The gauge *i* may be arranged so as, when the machine is in use, to come at the opposite end of the article to be operated on, or the feeding-table may have lengths measured off on it as indexes, and the feed of the article to be rolled be regulated by the operator in accordance therewith, and such measured indexes I claim as the equivalents of the gauge *i*.

What I claim as my invention, and desire to secure by Letters Patent, is—

1. Two plain surfaces, longitudinally converging and transversely parallel, and arranged with reference to each other so as to be operative in compressing wooden tenons and rounds by the motion of either, as described.

2. The subject-matter of the previous claim, in combination with a gauge, fixed or adjustable, for determining the length of the tenon or the position of the round, as described.

3. The subject-matter of the first claim, in combination with a bead, *n'*, attached to either or both, for the purposes set forth.

In testimony whereof, I, the said BENJAMIN D. SANDERS, have hereunto set my hand.

B. D. SANDERS.
